CLAIM

The ornamental design for a camera and mount assembly for a vehicle, as shown and described.

DESCRIPTION

FIG. 1 is a rear view of the camera and mount assembly for a vehicle in which the camera mount is separated from the camera and is positioned above the camera;

FIG. 2 is a left side view of the camera and mount assembly for a vehicle in which the camera mount is separated from the camera and is positioned above the camera;

FIG. 3 is a front view of the camera and mount assembly for a vehicle in which the camera mount is separated from the camera and is positioned above the camera;

FIG. 4 is a right side view of the camera and mount assembly for a vehicle in which the camera mount is separated from the camera and is positioned above the camera;

FIG. 5 is a perspective view of the camera and mount assembly for a vehicle in which the camera mount is separated from the camera and is positioned above the camera with the left, front, and top of the camera and mount assembly for a vehicle visible;

FIG. 6 is a perspective view of the camera and mount assembly for a vehicle in which the camera mount is separated from the camera and is positioned above the camera with the left, front, and bottom of the camera and mount assembly for a vehicle visible;

FIG. 7 is a perspective view of the camera and mount assembly for a vehicle in which the camera mount is separated from the camera and is positioned above the camera with the right, rear, and top of the camera and mount assembly for a vehicle visible;

FIG. 8 is a perspective view of the camera and mount assembly for a vehicle in which the camera mount is separated from the camera and is positioned above the camera with the right, rear, and bottom of the camera and mount assembly for a vehicle visible;

FIG. 9 is a rear view of the camera and mount assembly for a vehicle in which the camera mount is coupled to the camera;

(Continued)

FIG. 10 is a left view of the camera and mount assembly for a vehicle in which the camera mount is coupled to the camera;

FIG. 11 is a front view of the camera and mount assembly for a vehicle in which the camera mount is coupled to the camera;

FIG. 12 is a right view of the camera and mount assembly for a vehicle in which the camera mount is coupled to the camera;

FIG. 13 is a perspective view of the camera and mount assembly for a vehicle in which the camera mount is coupled to the camera with left, rear, and top of the camera and mount assembly for a vehicle visible;

FIG. 14 is a perspective view of the camera and mount assembly for a vehicle in which the camera mount is coupled to the camera with left, rear, and bottom of the camera and mount assembly for a vehicle visible;

FIG. 15 is a perspective view of the camera and mount assembly for a vehicle in which the camera mount is coupled to the camera with right, front, and top of the camera and mount assembly for a vehicle visible;

FIG. 16 is a perspective view of the camera and mount assembly for a vehicle in which the camera mount is coupled to the camera with right, front, and bottom of the camera and mount assembly for a vehicle visible;

FIG. 17 is a top view of the camera and mount assembly for a vehicle in which the camera mount is coupled to the camera; and,

FIG. 18 is a bottom view of the camera and mount assembly for a vehicle in which the camera mount is coupled to the camera.
